Primary Examiner — Manpreet S Matharu*Assistant Examiner* — Yolanda Robinson(74) *Attorney, Agent, or Firm* — Wolf, Greenfield & Sacks, P.C.(57) **CLAIM**

The ornamental design for a lever door handle lock, as shown and described.

DESCRIPTION

FIG. 1 is a front, top, right perspective view of a lever door handle lock;

FIG. 2 is a front, bottom, right perspective view thereof;

FIG. 3 is a front elevation view thereof;

FIG. 4 is a rear elevation view thereof;

FIG. 5 is a right side elevation view thereof;

FIG. 6 is a left side elevation thereof;

FIG. 7 is a top plan view thereof, the bottom plan view being a mirror image of the top plan view;

FIG. 8 is a rear, bottom, right perspective view thereof; and,

FIG. 9 is a rear, top, right perspective view thereof.

The dash-dash broken lines in the drawings depict portions of the lever door handle lock that form no part of the claimed design. The short dash-long dash lines in the drawings depict boundaries of the claimed design that form no part of the claimed design.

1 Claim, 9 Drawing Sheets(56)
